FLUSH DEVICE

George Schaser, Gary, Ind.

Application March 4, 1936, Serial No. 66,983

2 Claims. (Cl. 137—104)

This invention relates to a new and improved flush device; and more particularly to an improved combination valve and operating means therefor, adapted for use on a water-closet flush tank, and the like.

With the customary flush devices generally employed on water-closet flush tanks, it is observed that the valve closes rather slowly, in fact so slowly as to produce a lingering seepage of the water during the final stage of filling the flush tank and completely closing the valve. Such seepage soon causes a groove to be worn into one or both of the companion valve elements; and thereupon a continuous leakage takes place, which becomes very annoying to hear and which quickly ruins the valve and causes a considerable loss of water.

Another defect is observed in the arrangement and construction of the flush devices now on the market, in that it is not an easy matter to get at the companion valve elements for inspecting and repairing the same, without taking much time for loosening and removing a considerable number of screws and parts of the device.

It is an essential object of this invention to remedy the above noted defects, and to provide a flush device which is so arranged and constructed that the valve will be very promptly closed completely, and the annoying seepage of water, which has heretofore occurred with the ordinary valve devices, will be entirely avoided; and wherein, at the same time, the valve will not be closed so rapidly as to create injurious back-pressure or water-hammer.

It is another object of this invention to provide such a valve device which effects a positive and water-tight closure, preferably by employing a double or compound closing means.

It is a further object to provide a flush device so constructed that the valve elements and the gasket thereon can be readily inspected and replaced.

These and various other objects and advantages are attained with this invention, as will become apparent from the following description, taken in connection with the accompanying drawing wherein the invention is shown in its preferred form; it being understood that various other arrangements and forms of construction may be adopted in carrying out the objects and purposes of this invention.

In the drawing:

Fig. 1 is an elevational view of a flush device having my invention applied thereto.

Fig. 2 is a vertical sectional view thereof, taken

on line 2—2 of Fig. 1, showing the parts in the valve-closed position.

Fig. 3 is a vertical sectional view, similar to that shown in Fig. 2, but the parts being in position while the valve is open.

Fig. 4 is a plan view of the device.

Fig. 5 is an enlarged horizontal sectional view, taken on line 5—5 of Fig. 2.

In the drawing my invention is illustrated in its preferred form of construction, comprising a tubular stem 11 having a restricted sleeve portion or neck 12 extending integral from its upper end, thereby providing a shoulder 13 at the junction of the two, adapted to have a gasket 14 seated on the shoulder and surrounding the neck. The neck has its top 15 closed, and has openings or perforations 16 in its sides, which provide the valve openings for emitting the water which enters thru the stem 11. Said neck 12 provides the stationary valve element.

The stem 11 is provided with an annular flange 18 beneath which a gasket 19, of rubber or the like, is seated. Said gasket and a nut 20 which is placed below it on the threaded end 21 of the stem, provide means for mounting the stem water-tight in the usual opening provided in the bottom of the flush tank.

The movable valve member, which cooperates with the stationary valve member 12, includes a cap or sleeve member 22 which fits water-tight around member 12 and is slidable longitudinally thereon. It is closed at the top 22' of the sleeve, and has a bracket portion 23 thereabove. In its closed position member 22 covers the outlet openings 16, as shown in Fig. 2; and in its open position it leaves said openings 16 uncovered, as shown in Fig. 3. In its closed position valve sleeve 22 has its lower end seated water-tight upon the gasket 14, thus forming an additional water-tight seal for this valve.

This valve construction thus provides a double or compound water-tight seal or closure for the valve. The one is provided by means of the water-tight fit of sleeve 22 upon sleeve 12, in covering the openings 16; and the other is provided by the sleeve 22 having its lower end seated water-tight upon gasket 14, whereas the upper end 22' of this sleeve is closed. Consequently, even if long extended use and wear should impair the sealing fit between the two sleeves, yet the sealing fit between the lower end of sleeve 22 and gasket 14 would be sufficient to prevent leakage or seepage, as occurs in the ordinary valves of this type of device; and the gasket 14 can be

cheaply and readily replaced if necessary, for maintaining a water-tight seal.

A dome-shaped deflector 25 is preferably also provided, including an upper collar 26 which slidably embraces sleeve 22; and a lower internally threaded collar 27 depends from the bottom wall 28 of the deflector, being detachably mounted on the externally threaded upper part 29 of stem 11. The inner part 28' of wall 28 extends inwardly 10 from collar 27 and engages upon the marginal edge portion of gasket 14, for holding it in place. Slots 30 are provided in the outer part of wall 28, to emit the water which flows thru openings 16 and is then deflected by the dome-shaped portion 15 downwardly thru said slots.

The frame for supporting the valve operating means is of an open construction, and provides convenient access to the valve elements. It includes a pair of standards or supporting bars 31, 20 each of which is preferably formed from a metal plate that is substantially straight across its lower end 32 and has its two edge portions 31' bent inwardly to an increasing extent from the lower part toward the upper part 33, thereby 25 becoming channel-shaped at the upper part or end 33, substantially as indicated in the drawing. The pair of lower ends 32 of the pair of standards 31 are detachably secured, with screws or the like, to a pair of upturned lugs 34 provided on flange 30 18 of stem 11; and a head or top member 35 has a pair of depending lugs 36 secured in the two upper channel ends 33 of the standards 31, substantially as shown.

The means for operating the valve includes a 35 float-controlled quick-acting toggle mechanism 40 and an operating shaft 41 extending therefrom, thru an opening 42 provided in head member 35, to the bracket portion 23 on the movable valve sleeve 22. The shaft is detachably connected to the bracket portion 23, by a screw 43 or similar element which can be readily reached and removed thru the space between standards 31. The shaft 41 can then be swung aside and the valve sleeve 22 can be readily withdrawn from 45 valve sleeve 12, and the deflector 25 with its integral collar 27 can be unthreaded and removed from stem 11, whereupon the gasket 14 can be readily removed and replaced by a new one. The valve sleeves can thus be inspected by merely 50 removing screw 43 and withdrawing valve sleeve 22, and the gasket can likewise be readily replaced by removing only screw 43 and the deflector 25 and sliding sleeve 22 up from sleeve 12.

The toggle mechanism 40 includes a float-controlled lever 44, and a valve actuating lever 45, also spring means 46 which is pivotally connected with the two levers, so as to impart a quick or snap action from operating lever 44 to valve actuating lever 45 and therefrom to operating shaft 60 41 and the connected valve sleeve 22, and promptly close the valve openings 16 in sleeve 12 and seat sleeve 22 firmly upon gasket 14.

The operating lever 44 preferably has its main part 41 constructed from two bars, one pair of 65 the ends of said bars being pivotally mounted at the outer sides of a pair of lugs 48 which arise from head member 35, a pivot element 49 extending thru said lugs and the lever ends. Between said lugs 48 the valve actuating lever 45 is pivotally mounted upon the pivot element 49. Spacing washers 50 may be interposed between lever 45 and lugs 48, as shown.

Spring means 46 includes a casing or tube 51 closed at one end 52 from which extend spaced 75 perforated ears 53 engaging one end of actuating

lever 45 therebetween, a pin 54 extending thru said lever and said ears for pivotally connecting the lever with the spring means. A compression spring 55 is disposed in this tube 51, being confined between the closed end 52 and a pin 56 which is detachably mounted near the swingable ends of lever bars 47 and is adapted to move in a slot extending longitudinally of tube 51, while the toggle mechanism is in operation.

The valve actuating lever 45 is pivotally connected to the operating shaft 41, by a pivot pin 58, intermediate the pivot elements 59 and 54, and includes a hook or trigger-like stop portion 59 which is movable between spaced channel portions 60 extending from a tubular pocket 62 provided on head member 35. A spring 61 is seated in this pocket and urges hook portion 59 outwardly, to aid in depressing shaft 41 and valve sleeve 22 into the valve-closed position, as shown in Fig. 2. Said hook portion may bear against the wall of pocket 62 or against standard 31 to limit its movement in the valve-open direction, as shown in Fig. 3; while its movement in the valve-closed direction is limited by the firm pressing of sleeve 22 upon gasket 14.

The float-controlled operating lever 44 has an arm or rod 63 adjustably connected to the bars of its main part 41, said rod having the customary float ball 64 attached to its outer end. The adjustable connection is preferably provided by the use of a member 65 which includes a socket wherein the rod 63 is threaded, said member also including a plate portion 66 which is pivoted by a pin 67 between the swingable ends of bars 47 of lever 44. A thumb screw 68 is placed in the extreme ends of said bars 47 and extends thru an arcuate slot 69 provided in plate 66, which permits swinging of plate 66 on pivot pin 67 for the vertical adjustment of rod 63 and float 64 with respect to the main part of lever 44, whereby to 40 control the position of the water-level in the flush tank.

When operating lever 44 has been moved sufficiently, thru the action of float 64, so that the center line of this lever has passed beyond the 45 center line thru pivot pins 54, 58 and 49, then the compression spring 55 becomes operative, which is at that position compressed, and with a quick snapping action moves the valve actuating lever 45 with the shaft 41 and the movable 50 valve sleeve 22 from one of the valve positions, as shown in Figs. 2 and 3, to the other. The compression spring 61, which is weaker than spring 55, aids in promptly moving valve sleeve 22 into its closed position and in holding the 55 valve firmly closed upon the gasket 14. The valve openings 16 are made of the proper size and number to afford the prompt closing of the valve, and at the same time to prevent any extremely rapid closing thereof which might produce detrimental back-pressure or water-hammer.

I claim:

1. A flush device comprising means adapted to be mounted in a flush tank, a stationary valve member on the upper end of said means, a movable valve member mounted on the stationary valve member, spaced frame standards arising from said mounting means, a head mounted upon the standards, an operating lever and pivot means pivoting the lever at one end to means on said head, float-carrying means adjustably mounted on the other end of said lever, a valve actuating lever pivoted by said pivot means onto said means on the head and having a stop portion extending beyond the pivot means, an operating shaft 70

extending thru the head and between the standards and being pivotally connected to the actuating lever and to the movable valve member, spring means engaging said stop portion to urge the actuating lever and shaft to the valve-closed position, and spring means pivotally connected with one end to the free end of said actuating lever and with the other end to said operating lever between said float-carrying means and said pivot means, whereby to operate the movable valve member with a quick motion for promptly closing the valve completely.

2. In a flush valve device containing a stationary valve member and a movable valve member thereon and means adapting the same to be mounted in a flush tank, also supporting means arising from the mounting means; a mechanism on said device for operating the movable valve member and closing it completely with a quick

action, said mechanism consisting of a head member mounted on said supporting means and provided with spaced lugs thereon and a pocket containing a spring therein, an operating lever and means whereby it is pivoted with one end to said lugs, float-carrying means adjustably mounted on the other end of said lever, a valve actuating lever pivoted by said pivot means onto said lugs and including a stop arm which engages said spring and is urged thereby to the valve-closed position, an operating shaft extending thru the head and being pivotally connected with the actuating lever and with the movable valve member, and compression spring means pivotally connected with one end to the free end of said actuating lever and with the other end to said operating lever between said float-carrying means and said pivot means.

GEORGE SCHASER.
